(57) **CLAIM**

The ornamental design for an indicia displaying device for noise making, as shown and described.

DESCRIPTION

FIG. 1 is a front perspective view of an indicia displaying device for noisemaking showing my new design;

FIG. 2 is a back perspective view thereof;

FIG. 3 is a front elevational view thereof;

FIG. 4 is a back elevational view thereof;

FIG. 5 is a left side elevational view thereof, the right side elevational view being a mirror image of the side shown;

FIG. 6 is a top plan view thereof; and,

FIG. 7 is a bottom plan view thereof.

The broken lines are included for the purpose of illustrating portions of the indicia displaying device for noisemaking that form no part of the claimed design.
